Calif., a corporation of Nevada.

Application December 9, 1932, Serial No. 646,469

9 Claims. (Cl. 179—171)

My invention relates to amplifiers, and particularly to amplifiers designed for operation at the higher radio frequencies.

Among the objects of my invention are: To provide an amplifier capable of providing large amounts of output power; to provide an amplifier having extremely low output impedance and relatively high input impedance; to provide an amplifier wherein the output circuit is substantially without effect upon the input circuit; to provide an amplifier which may be used almost at the point of self-oscillation without affecting materially the input constants of the amplifier; and to provide an amplifier wherein the type of vacuum tube characterized by a plate-like control electrode mounted in opposition to a similarly formed output electrode may be utilized to provide large power outputs at relatively high efficiency.

Other objects of my invention will be apparent or will be specifically pointed out in the description forming a part of this specification, but I do not limit myself to the embodiment of my invention herein described, as various forms may be adopted within the scope of the claims.

Referring to the drawings:

Figure 1 is a view, partly in elevation and partly in section, of a tube adapted for use in the amplifier of this invention.

Figure 2 is a transverse section of the tube shown in Figure 1, the plane of projection being on the line 2—2 of the first figure.

Figure 3 is a fragmentary sectional view of the tube, taken on the line 3—3 of Figure 2, and showing the auxiliary accelerating electrode.

Figure 4 is a circuit diagram of the amplifier.

Figure 5 is a similar diagram showing a modified form of the amplifier.

The invention involves the use of a vacuum tube having the usual cathode, anode, and control electrode, and, in addition, an accelerating electrode whose function is to increase the mutual conductance or transductance of the tube by increasing the velocity of electrons leaving the filament, and neutralizing or partially neutralizing the space charge thereof. Such an electrode, it will be seen, has a certain degree of control over the space current, and this control is in the same sense as that of the control electrode, i. e., a negative swing in potential of the control electrode decreases the space current, while a positive swing increases this current.

The input circuit of the amplifier is connected to the control electrode in the usual manner, while the anode connects to the output circuit.

The accelerating electrode is coupled to the anode in such a manner as to augment the effect of the control electrode on the space current; i. e., so that a decrease in space current impresses a less positive potential upon the accelerating electrode. In this manner the effective transductance of the tube is very greatly increased, as is the effective amplification constant, but there is no reaction upon the input circuit of the device as is the case where regeneration or feed-back is used. It is therefore possible greatly to increase the amplification and power output of the tube without introducing the distortion present in regenerative amplifiers. Furthermore, since the accelerating electrode is operated at a positive potential, the output impedance of the tube may be made very low, and large effective power output may be obtained even with relatively low amplification factors.

In order to take fullest advantage of the latter feature of the device, it is preferable that the tube used be of the type wherein a plate-like control electrode is positioned on one side of a filamentary cathode, while the anode or plate is positioned on the other side and at a greater distance therefrom. A preferred form of such a tube is illustrated in Figures 1, 2 and 3, wherein an envelope 1 is provided with side stems 2 through which are sealed support rods 4 for holding the plate-like control electrode 5. On the opposite side of the envelope a similar set of side stems 6 and support rods 7 hold the anode 9. Between the control electrode and the anode the filament 10 is positioned, the filament being much more closely adjacent the control electrode than the anode.

The accelerating electrode, which is of reticulated or grid-like form is positioned between the anode and the filament, being supported in this case by a band or clamp 12 surrounding a re-entrant stem 14 at one end of the tube.

A tube of the character shown, but without the accelerating electrode, is capable of handling relatively large amounts of power, but is limited as to amplification. Thus a commercially built tube of this type will have an amplification constant of perhaps three or four, but its output impedance will be low—of the order of 500 or 600 ohms.

The addition of the accelerating electrode 11, which should be operated at a potential positive with respect to the cathode, has two effects. First, it greatly decreases the effective capacity between the control electrode and the anode, thus reducing the reaction between the output and input circuits of the device, and second, it still fur-

ther decreases the output impedance of the device.

The application of the tube to the amplifier of my invention is shown schematically in Figure 4.

- 5 An input circuit comprising leads 20 and 21 connects to the cathode 10 and control electrode 5. The anode or plate 9 is connected to an output circuit comprising an inductor 22 tuned by a condenser 24, a tap 25 on the inductor being connected to ground through a by-pass condenser 26. Anode current is supplied to the output circuit from a battery or other suitable source 27, the accelerating electrode 11 being connected to an intermediate point on this battery through 10 a choke-coil 29. The electrode 11 is also connected to the terminal of the tuned output circuit opposite that to which the anode 9 is connected, through a blocking condenser 30.

The operation of the circuit is as follows:

- 20 When an impulse applied to the input circuit swings the control electrode negative, the space current between cathode and anode is decreased, swinging the anode positive in accordance with the well known functioning of tubes of this type. 25 The decrease in current through the inductor 22 induces a negative potential at the end of the coil opposite to the anode connection, and this potential is applied to the accelerating electrode 11, superposed upon the constant potential applied thereto by the battery 27 through the choke-coil 29. The decrease in positive potential applied to this electrode serves further to decrease the space current, thereby tending to increase the positive potential on the anode and augment the effect produced thereon by the control electrode. A positive potential applied to the control electrode 5 has the opposite effect, swinging the anode negative and the accelerating electrode positive.

- 40 There is, however, no reaction produced on the input circuit by this action. Not only is the control electrode shielded from the plate by the accelerating electrode, but since the control electrode actually swings in the opposite sense to the swing in plate potential, this has a reverse effect to that of the plate, and completely cancelling out any tendency toward capacity feedback into the input circuit.

- 50 The amount by which the auxiliary electrode augments the effect of the control electrode may be controlled by varying the point at which the tap 25 connects to the inductance 22. It is possible under certain circumstances to increase this effect until the circuit becomes self-oscillatory, 55 although this point is not reached as readily as it would be were the accelerating electrode operated at a mean negative potential with respect to the filament. At points below self-oscillation, however, there is very much less tendency to produce distortion through the effect of this augmentation than is the case where feedback or 60 regeneration is used. It is to be noted that the entire circuit still remains primarily under the control of the control electrode 5, and that there is no "feedback" to this circuit. Accordingly 65 there is no effective reduction of resistance in this circuit, and hence there is less tendency toward excessive amplification on a single frequency than in circuits in which feedbacks occur. 70 The amplifier is therefore applicable to audio frequency circuits or other circuits where tuning is undesirable, the only difference in such applications being that the tuning condenser 24 is omitted.

- 75 Power may be withdrawn from the output cir-

cuit either through the leads 31 and 32, or by making coil 22 the primary of a transformer.

A slight modification of the circuit is shown in Figure 5. In this instance the connections, although differently arranged in the diagram, are essentially the same as in Figure 4, the difference being that a neutralizing condenser 35 connects between the electrode 11 and the control electrode 5. This arrangement is applicable for use with tubes wherein the shielding effect and neutralizing effect of the accelerating electrode 11 are not sufficient completely to counteract capacity coupling between the anode 9 and the control electrode 5.

10 It is to be understood that the invention is not limited to tubes having the plate-type of control electrode. The ordinary "screen grid" type of tetrode may be used, either the inner or the outer grid being used as the control electrode, the other grid being connected as an accelerating electrode. 15 It is usually preferable, however, to operate such tubes with the inner grid as the accelerating electrode and the outer grid as the control electrode, since this results in minimum impedance in the tubes. Where such tubes are used, however, the 20 effective impedance of the tube will be much greater than in the cases described above.

25 In practice I have found that the connection as shown will raise the effective amplification constant of a tube of this class approximately three-fold, and at the same time will reduce the effective $a-c.$ impedance of the tube approximately to one-half. It will therefore be apparent that the effectiveness of the amplifier, as measured by the watts output divided by the watts input, 30 is greatly increased, as is the total amount of power which the amplifier will deliver.

35 I claim:

1. The combination with a thermionic tube having a cathode, a plate electrode on one side of said cathode, a control electrode on the other side of said cathode, and an accelerating electrode between said cathode and said anode, of means for applying impulses to said control electrode, and means for coupling said accelerating electrode to said plate electrode in such phase relationship that potential changes in said plate electrode initiated by said control electrode are augmented by said accelerating electrode.

40 2. The combination with a thermionic tube having a cathode, a plate electrode on one side of said cathode, a control electrode on the other side of said cathode, and an accelerating electrode between said cathode and said anode, of an input circuit connected to said control electrode, an output circuit connected to said plate electrode, and a connection coupling said accelerating electrode to said plate electrode to impress on said accelerating electrode a potential of opposite sign to that on said plate electrode.

45 3. The combination with a vacuum tube having a cathode, an anode on one side of said cathode, a control electrode on the other side of said cathode, and an accelerating electrode between said anode and cathode, of an input circuit connected to said control electrode, an output circuit connected to said anode, and coupling means connecting said anode and said auxiliary electrode in such phase relation that voltages derived from said output circuit affect said accelerating electrode to augment the effect of said control electrode on the current flow.

50 4. The combination with a vacuum tube having a cathode, an anode on one side of said cath-

ode, a control electrode on the other side of said cathode, and an accelerating electrode between said anode and cathode, of an input circuit connected to said control electrode, an output circuit connected to said anode, coupling means connecting said anode and said auxiliary electrode in such phase relation that voltages derived from said output circuit affect said accelerating electrode to augment the effect of said control electrode on the current flow, and means for preventing reaction between said output circuit and said input circuit.

5. The combination with a vacuum tube having a cathode, an anode on one side of said cathode, a control electrode on the other side of said cathode, and an accelerating electrode between said anode and cathode, of an input circuit connected to said control electrode, an output circuit including an impedance element connected 10 to said anode, and coupling means between said impedance element and said accelerating electrode for impressing thereon voltages of opposite phase from the voltage on said anode.

6. The combination with a vacuum tube having a cathode, an anode on one side of said cathode, a control electrode on the other side of said cathode, and an accelerating electrode between said cathode and said anode, of an input circuit connected to said control electrode, an output circuit connected to said anode, and means coupling said anode and said accelerating electrode for transferring therebetween voltages reversed in phase relation.

7. The combination with a vacuum tube having a cathode, an anode on one side of said cathode, a control electrode on the other side of said cathode, and an accelerating electrode between

said anode and cathode, of an input circuit connected to said control electrode, and a tuned output circuit, one end of said tuned circuit being connected to said anode and the other connected to said accelerating electrode, whereby 5 the potentials of said anode and said auxiliary electrode are maintained in opposite phase relationship.

8. The combination with a vacuum tube having a cathode, an anode on one side of said cathode, a control electrode on the other side of said cathode, and an accelerating electrode between said anode and cathode, of an input circuit connected to said control electrode, a tuned output circuit, one end of said tuned circuit being connected to said anode and the other connected to said accelerating electrode, and means for maintaining the alternating current potential of said cathode intermediate that of said anode and accelerating electrode.

9. The combination with a vacuum tube having a cathode, an anode on one side of said cathode, a control electrode on the other side of said cathode, and an accelerating electrode between said anode and cathode, of an input circuit connected to said control electrode, a tuned output circuit, one end of said tuned circuit being connected to said anode and the other connected to said accelerating electrode, means for maintaining the alternating current potential of said cathode intermediate that of said anode and accelerating electrode, and means for maintaining the mean potential of said cathode negative with respect to both said anode and said accelerating electrode.
